UNITED STATES PATENT OFFICE.

WILLIAM WATSON STOKES, OF ANNA, ILLINOIS.

BENDING-MACHINE.

SPECIFICATION forming part of Letters Patent No. 300,159, dated June 10, 1884.

Application filed January 28, 1884. (No model.)

To all whom it may concern:

Be it known that I, WILLIAM W. STOKES, of Anna, county of Union, Illinois, have invented a new and Improved Bending-Machine, 5 of which the following is a full, clear, and exact description.

My invention consists of an improved contrivance of bending-levers, anvil-block, adjustable formers, and a gage whereby it is designed to provide a simple and efficient machine adapted for the use of blacksmiths, carriage-makers, and other iron-workers to bend stirrup, clip, and other irons by hand; all as hereinafter fully described.

Reference is to be had to the accompanying drawings, forming part of this specification, in which similar letters of reference indicate corresponding parts in all the figures.

Figure 1 is a perspective view of my improved bending-machine. Fig. 2 is a side elevation of the pivot-bolt and section of a sleeve employed for the pivot of the principal bending-lever. Fig. 3 is a side elevation and section of the washer employed for the pivot 25 of the secondary lever. Fig. 4 is a side elevation of a former to be used on the principal bending-lever. Fig. 5 is a plan view of the bending-machine, showing the manner of bending a clip. Fig. 6 is a plan view of the 30 machine, showing the manner of bending a bar into an obtuse angle; and Fig. 7 is a plan of the machine, showing the manner of bending a bar into two reverse right angles.

I construct a suitable bed-plate, *a*, of metal 35 with three parallel slots, *b*, *c*, and *d*, and located with relation to each other as shown, or substantially so, for the purpose of adjustably connecting the working parts. I also provide said bed-plate with an anvil-block, *e*, and 40 a gage-bar, *f*, both of which are firmly attached to said bed-plate; and the gage-bar has a shifting gage-stop, *g*, fitted to it for being set on said bar at any point for gaging the distance of the bends from the ends of the bars.

Alongside of the anvil-block *e*, I arrange a former-block, *h*, having one square end, *i*, and one half-round end, *j*, and I secure the same with a bolt, *k*, nut *l*, and washer *m*, so as to bind it fast to the bed-plate either parallel 45 with the anvil-block *e*, as in Figs. 1, 5, and 7, or obliquely to it, as in Fig. 6, the bolt *k* extending down through the bed-plate and draw-

ing against the under side of the said plate. I use a square washer for this bolt and construct it with a rib, *o*, Fig. 1, on the lower 55 side as wide as the slot *n* through the former, for the bolt to project into the slot for binding the block more firmly and preventing the washer from turning with the nut.

I propose to employ formers *h* of different 60 forms and sizes, according to the different forms and sizes of bars and the bends to be made in them, said forms to be changed at will by removing the nut *l* and washer *m*; and in order to prevent the bolt *k* from dropping out of its 65 place while changing the formers, I propose to provide a keeper consisting of a small plate, *p*, through which the bolt passes, and which I fit into the slot *b*, so that it will not drop out, by wedging it fast in said slot or securing said 70 plate therein by any other means. The bolt *k* is made square or with flat sides in the parts fitting the slot *b* of the bed-plate and the slot *n* of former, to effectually prevent the former 75 from turning by the stress on it of the bars being bent.

In the slot *d*, I fit a pivot-bolt, *q*, for the fulcrum-pivot of the main bending-lever *s*, said bolt being adjustable along the slot for locating the lever as desired relatively to the anvil 80 *e*, and it has a sleeve, *t*, on the part whereon the lever turns for the nut to jam on in securing the lever; also for sustaining the wear and to facilitate taking up the slack by renewal when worn loose.

A short distance along the lever *s* from the pivot-bolt *q* said lever is recessed in the lower side to receive the forming-block *u* and the lever *v* between it and the surface of the bed-plate, and said lever also has a vertical longitudinal slot, *w*, along it a suitable distance from the shoulder of the recess, for inserting the bolts *x* and *y*, which connect the lever *v* and former *u*, respectively, to the lever *s*. Said bolts are flat-sided in the parts passing through 90 the slot *w* of lever *s*, to prevent them from turning; but the pivot-bolt *x* of the lever *v* is round on the part on which said lever turns, and it has a small countersunk head, *z*, to enter the hole of the lever flush with the under 95 side, and allow the lever to work against the surface of the table. The former *u* is to be set close to the end of lever *v* when said lever is set at a distance from the shoulder *a'*, and is 100

used for bending a bar around former *h*, and forms an adjustable prolongation of the side wall of lever *s* back of the shoulder *a'*, which prevents the bar from bending into the cavity 5 behind the ends of the lever *v*, as it would in bending around the angle of former *h* without said former *u*; but said former *u* is more particularly employed when a reverse angle is to be made, as represented in Fig. 7, the lever *v* 10 being thus disconnected from lever *s* and connected to the bed-plate by inverting it and passing its bolt *x* through the slot *c*. In such use of the machine the pivot-bolt *q* of the lever *s* will be shifted along more to the back edge 15 of the bed-plate, for enabling said former *u* to be suitably placed with relation to former *h*. When the bar is to be bent in the form of a clip, as in Fig. 5, or into an obtuse angle, as in Fig. 6, the former *u* will not be used. It 20 will be seen that the lever *s* bends the bar *b'* around to the end of former *h*, and then the lever *v* bends it around to the side of said former for making clips, or around the former *u* to make the reverse angles, as the case may 25 be.

The lever *s* may be fastened to the bed by shifting its bolt *q* to the slot *c*, when it may be desired. The bed *a* will have a strong lug formed on the under side, suitably for fastening it to a strong bench, such as represented 30 in Fig. 1.

Having thus described my invention, I claim as new and desire to secure by Letters Patent—

1. The combination of the anvil *e*, former *h*, and lever *s*, with a bed-plate, *a*, having slots 35 *b c*, said former *h* having a slot, *n*, for its fastening-bolt, and said former and lever being adjustable along the slots of the bed-plate, and former *h* being adapted to be set obliquely to the anvil-block, substantially as described. 40

2. The combination of the anvil-block *e*, adjustable former *h*, and lever *s*, with bed-plate *a*, having slots *b* and *c*, and the lever *v*, said lever *v* being pivoted to and adjustable along lever *s*, substantially as described. 45

3. The combination of the anvil-block *e*, adjustable former *h*, lever *s*, former *u*, and lever *v*, with the bed-plate *a*, having slots *b c d*, said lever *v* and former *u* being adjustably connected to said lever *s*, and said lever *s* being 50 removable to and connectable in slot *c*, substantially as described.

4. The combination of the bed-plate *a*, anvil-block *e*, adjustable former *h*, levers *s* and *v*, and the gage-bar *f* and adjustable stop-gage *g*, substantially as described. 55

WILLIAM WATSON STOKES.
